(57) **CLAIM**

The ornamental design for a saddle pad cover, as shown and described.

DESCRIPTION

FIG. 1 is a top front perspective view of a saddle pad cover, showing my new design, shown with a zipper in a closed position;

FIG. 2 is a top plan view thereof;

FIG. 3 is a front elevation view thereof;

FIG. 4 is a rear elevation view thereof;

FIG. 5 is a bottom plan view thereof;

FIG. 6 is a right elevation view thereof, with the left elevation view being a mirror image thereof; and,

FIG. 7 is a top front perspective view thereof, shown with the zipper in an open position.

The broken lines shown in the drawings depict a portion of the article that forms no part of the claimed design.

1 Claim, 4 Drawing Sheets
